UNITED STATES PATENT OFFICE.

CALEB T. CLEAVELAND, OF KINGSTON, NEW YORK.

CAR-STARTER.

SPECIFICATION forming part of Letters Patent No. 416,994, dated December 10, 1889.

Application filed April 23, 1889. Serial No. 308,291. (No model.)

To all whom it may concern:

Be it known that I, CALEB T. CLEAVELAND, of Kingston, in the county of Ulster and State of New York, have invented a new and Improved Car-Starte, of which the following is a full, clear, and exact description.

This invention relates to car-starters, the object of the invention being to provide an attachment for tramway or street cars, where-
10 in the parts shall be so arranged that the preliminary pull of the horses will be brought to bear with increased effect upon the forward axle of the car; a further object of the invention being to relieve the horses from the
15 shock or jar incident to the initial pull.

To the ends above named the invention consists, essentially, of a ratchet arranged for connection with the car-axle, a pawl mounted in a swinging frame and arranged to engage
20 the ratchet, cables or chains connected to said frame, one of said cables or chains being connected to a spring, while the other is connected to a transverse draft-lever, all as hereinafter fully explained, and specifically
25 pointed out in the claims.

Reference is to be had to the accompanying drawings, forming a part of this specification, in which similar figures and letters of reference indicate corresponding parts in all the
30 views.

Figure 1 is a plan view of a portion of my improved car-starter. Fig. 2 is a side view thereof. Fig. 3 is a detail view on line x x of Fig. 1. Fig. 4 is a detail view illustrating the construction of the ratchet. Fig. 5 is a detail view illustrating the connection between the axle and the rear end of the stop or limit pin frame, and Fig. 6 is a detail view illustrating the arrangement of the pawl and
35 its supporting arm or lever.

In the drawings, 10 represents a ratchet that is made in sections a and b , both sections being flanged at c to receive bolts 11, by means of which the ratchet-sections are
40 clamped to the car-axle 12. In addition to the flanges c , the ratchet-sections are formed with laterally-extending semicircular flanges d , which, when the parts are clamped to the axle, form bearing-sleeves upon which a box
45 or housing 14 is mounted. This box or hous-

ing 14 is provided with laterally-extending flanges e , which fit against one-half of the bearing-sleeve and extend forward beyond said sleeve, there to receive boxes 15, that are held to place by straps 16, said straps being
50 apertured to receive tap-bolts 17, that engage the forwardly-extending projections of the housing-flanges.

Within the housing 14, I pivotally mount a lever 18, the forward end of said lever being
55 bifurcated to receive a pawl 19, that is pivotally mounted between the members of the bifurcated-lever end. The lower rear end of the lever 18 is bent inwardly, in order that it may at times bear against an anti-friction
60 roll or pin 20, supported by a frame 21. The frame 21 consists of a bar f , to the forward end of which there are connected laterally and forwardly extending bars g and g' , and to the bars of the frame there are bolted hook-
65 like clips 23, that engage the car-axles, as illustrated, the clip carried by the bar f engaging the rear axle, while the clips carried by the bars g g' engage the forward axle at
70 either side of the housing-flanges, as shown.

The upper face of the housing 14 is segmental and concentric with the axis of the shaft to which the housing is connected, and in this upper face there are formed two grooves h and i , adapted to receive cables or chains 24 and
75 25, the cable or chain 24 being secured to the forward end of the housing and to a spring
30, said spring being a leaf-spring, a coil-spring, or any other proper form of spring—
80 such, for instance, as that shown in the drawings. The cable or chain 25 is connected to the rear end of the housing 14 and to a transverse draft-lever 26, that is pivotally connected to one of the car-sills, the opposite end of the lever riding beneath the opposite sill and
85 within a housing formed by a strap 27, the central portion of the lever being upheld by a second strap 28.

To the center of the lever 26, I connect the draw-bar 29, and the forward end of this bar
90 29 is supported by a suspending-arm 30, the lower end of which is bifurcated to receive the draw-bar, the upper end of the arm 30 being connected to a swivel-eye 31, that is supported in any proper manner in advance of
95 100

the dash-board, the arrangement being such that the draw-bar may swing forward and back and laterally, this latter movement being necessary when the car is passing about 5 a curve.

From the construction above described it will be seen that when the car is at rest and the draw-bar freed from tension the several parts of the starter will assume the positions 10 in which they are represented in the drawings. Then if the horses be started forward the lever 26 will move in the direction of the arrow shown in connection therewith in Fig. 1, the housing 14 being drawn forward in the direction of its arrow against the tension of the spring 36, and as the housing moves forward the eccentric section of the lever 18 will bear upon the anti-friction roll or pin 20 and the lever will be tilted to a position such as to 15 20 carry the pawl 19 into engagement with the teeth of the ratchet 10, and any continued pull upon the part of the horses will cause the axle to revolve in a proper direction to advance the car. After the car has been 25 started the lower end of the lever 26 will pass above the anti-friction roll or pin 20, and the lever will drop back onto a stop or limit pin 1, carried by the housing 14, and in so dropping back the pawl 19 will be freed from 30 engagement with the ratchet 10, this arrangement being adopted in order to prevent the continual clicking and all undue wear of the parts. Then when the tension on the draw-bar is relaxed the spring 36 will return the 35 parts to the position in which they are shown in the drawings, the lever 18 being guided to the rear of the anti-friction roll or pin 20 by an inclined-faced projection *n*, formed at its lower end.

40 By housing the lever 26 within the loops formed by the straps 27 and 28 I limit the forward movement of the lever, as will be readily understood.

By connecting the draw-bar with the spring 45 36, as hereinbefore set forth, I relieve the horses from the shock which they would otherwise experience if the connection between the draw-bar and the car were an unyielding one, as will be readily understood.

50 It will of course be understood that a duplicate of the construction hereinbefore described would be applied to the rear axle of the car for use when the car is traveling in an opposite direction.

Having thus described my invention, I claim 55
as new and desire to secure by Letters Patent—

1. In a car-starter, the combination, with a ratchet-wheel arranged for connection with the car-axle, of a housing mounted to turn upon said axle, a lever and pawl mounted 60 within the housing, cables or chains connected to the housing, a spring to which one of the cables is in turn connected, a draw-bar and connections, substantially as described, between the draw-bar and the other chain or cable, as and for the purpose stated.

2. In a car-starter, the combination, with a draw-bar, of an arm by which said bar is supported, a swivel-eye to which the arm is pivotally connected, a pivotally-mounted transverse lever, to which the inner end of the draw-bar is secured, a ratchet-wheel connected to the car-axle, a housing mounted to turn about the axle, a lever mounted within the housing, a pawl pivotally connected to the 70 lever and arranged to engage the ratchet, an anti-friction roll or pin, against which the lever at times bears, cables or chains connected to the housing, one of said cables being connected to the transverse lever, and a 75 spring to which the other cable is connected, substantially as described.

3. In a car-starter, the combination, with the draw-bar 29, of an arm 30, to which the draw-bar is pivotally connected, a swivel- 85 eye 31, to which the arm is connected, a transverse lever 26, pivotally connected to one of the car-sills, a strap 27, which supports the opposite lever end, a ratchet 10, formed with bearing-flanges *d* and arranged for connection with the car-axle, a housing mounted upon the bearing-sections *d* and formed with a segmental face, a lever pivotally mounted within the housing, a pawl carried by the lever and arranged to engage the ratchet, a 95 pin or anti-friction roll 20, against which the lever at times bears, cables or chains 24 and 25, connected to the housing, the cable 25 being connected to the lever 26, and a spring 36, to which the chain or cable 24 is connected, 100 substantially as described.

CALEB T. CLEAVELAND.
